CLAIM

The ornamental design for a clasp for bracelet, as shown and described.

DESCRIPTION

FIG. 1 is a front elevation view of the clasp for bracelet showing my new design with the clasp shown separate from the bracelet, the top clasp and the bottom clasp are identical with the top clasp in an unclasped position of use and the bottom clasp in a closed position;

FIG. 2 is an enlarged front perspective view thereof, in an unclasped position of use;

FIG. 3 is an enlarged bottom perspective view thereof;

FIG. 4 is an enlarged side perspective view thereof in the closed position with placement of free end bracelet bands attached to the engageable clasp device;

FIG. 5 is an enlarged bottom perspective view of the clasp for bracelet in an unclasped position of use with placement of free end bracelet bands attached to the engageable clasp device;

FIG. 6 is a side elevation view of the clasp for bracelet in a second embodiment without the bottom clasp;

FIG. 7 is a top elevation view thereof; and,

FIG. 8 is a front elevation view thereof.

The features shown in broken lines in the drawing depict portions of the design that form no part of the claimed design.
